EVAPORATOR CONSTRUCTION

Harold E. Wheeler, Chicago, Ill.

Application April 7, 1944, Serial No. 529,965

2 Claims. (Cl. 62—126)

1

This invention relates to refrigerator constructions in general, and more particularly to the construction on the inside of the refrigerator. More specifically, the invention relates to an arrangement of shelving and cold plates within the interior of the refrigerator.

The primary object of the present invention is the provision of a new and improved method and arrangement of positioning cold plates continuously by bending the cold plate back and forth upon itself so as to provide for the proper amount of refrigeration area within the box or refrigerator, and at the same time use the cold plate as shelving.

A further important object of the invention resides in the arranging and positioning of a cold plate within the inside of the refrigerator by bending the cold plate in step formation so as to provide shelves within the interior of the refrigerator, and at the same time insure a sufficient amount of cold plate area so that the proper refrigeration within the refrigerator may be obtained.

Numerous other objects and advantages will be apparent throughout the progress of the following specification.

The accompanying drawing illustrates a selected embodiment of the invention, and the views therein are as follows:

Fig. 1 is a detail vertical sectional view showing the interior of one form of refrigerator with which the invention is incorporated;

Fig. 2 is a detail sectional view at right angles to Fig. 1;

Fig. 3 is a detail perspective view showing one form of cold plate material which is bent back and forth upon itself to provide spaced parallel shelving;

Fig. 4 is a detail sectional view on the line 4—4 of Fig. 3; and

Fig. 5 is a detail perspective view showing grill or mesh-work which may be applied on top of the projections or protuberances if desired.

The particular construction herein shown for the purpose of illustrating the invention comprises a refrigerator 1 having enclosing walls 2. One wall is provided with an opening therein to permit access to the interior of the refrigerator, there being one or more doors 3 provided for closing the opening.

A practical application for arranging a surface of sufficient cooling area in the interior of the refrigerator is by means of a cold plate construction. The cold plate construction may assume various forms and adaptations and may consist

2

of sheets secured together with proper channels between the sheets so as to permit proper flow of refrigerant material through the cold plate construction. The particular type of cold plate construction herein shown for illustrative purposes comprises an extruded metal cold plate construction, whereby there is formed by the extrusion process a cold plate construction 4 comprising opposed surfaces 5 and 6. Protuberances or projections 7 spaced a predetermined distance apart extend upwardly from the surface 5. These spaced longitudinal projections or protuberances, during a continuous extruding process, are formed integral with the plate construction 4 and are provided with longitudinal bores or openings 8 to permit the flow of refrigerant therethrough. The protuberances 7 are spaced close enough together so that the entire surface is adapted to be cooled by the refrigerant passing through the longitudinal openings 8. The cold plate construction of the above type has been used for refrigerator cooling purposes; however, a certain length of cold plate has been cut to the desired length and positioned within the refrigerator, particularly in close proximity to the interior walls of the refrigerator. The shelves, usually of metal mesh or wire, have been supported on clips or brackets so that articles to be cooled may be supported by these shelves.

30 The present invention contemplates the use of a cold plate construction whereby a continuous or single length of cold plate material is bent back and forth upon itself to provide not only the required cooling surface, but also to provide shelves.

35 There is disclosed in Fig. 3 a single length of cold plate construction 4 arranged parallel to the upper and lower surfaces of the box to provide a shelf 9. The sheet of cold plate material 4 is bent at 10 to provide an end section 11. The material 40 is then again bent at 12 to provide a shelf 13 which is parallel to the shelf 9. The material is then bent at 14 to provide an end section 15. The material is again bent at 16 to provide a shelf 17 which is parallel to the shelves 13 and 9. If additional shelves are required, they are formed by bending the material along the lines 18 and 19 to provide spaced lower shelves 20. There may be as many bends in the single continuous length of cold plate material 4 as is necessary to provide sufficient cooling area, as well as to provide sufficient shelving space.

45 A relatively deep box 1, as herein shown, may only require a certain area of cooling surface to cool the box properly, and therefore it may be desirable not to have the cold plate construc-

tion 4 a width equal to the full depth of the box. In such cases the back and forth flat plate construction may be provided to extend outwardly a predetermined distance, as shown in Fig. 2, and the shelf space supplemented by conventional grill or wire shelves 21, 22, and 23 in alignment with the cold plate shelves 13, 17 and 20, respectively.

The bending back and forth of a continuous sheet of cold plate construction material 4 will in alternate shelves, such as 9 and 17, have the protuberances 7 projecting upwardly from the upper surface 5. In such cases a wire mesh or grill section 24 may be supported on the top of the protuberances 7 to provide a flush surface for the material which is to be supported.

The invention provides an extremely economical method for the interior construction of a refrigerator wherein the shelves act as the cooling area, or, stating it in the reverse, wherein the cooling plates act as the shelves for the refrigerator. The construction herein shown has been embodied in a practical device and it has been found that the cost of the interior shelving and cooling arrangement of a refrigerator has been reduced by approximately two-thirds. Also, in standard boxes the material may be cut to single lengths so that it may be economically stored without taking up much room, and, in fact, the material may be so shipped with the refrigerator and then bent at the time the refrigerator is installed for use. In most instances, however, it has been found desirable to bend the material to the proper configuration and install it within the box by means of suitable supporting brackets 25, Figs. 1 and 2.

The pipe connections from the compressor for communication with the openings 9 are not herein shown but it is, of course, understood that the proper refrigerant supply lines are properly connected to permit a circulation of fluid from the compressor through the cold plates, then draining back to the compressor.

The invention provides for the use of a single section of cooling plate construction bent back and forth upon itself to provide supporting shelves, all of which are properly cooled and all of which provide for the proper cooling area required, thereby conserving space and reducing costs to a minimum.

Changes may be made in the form, construction and arrangement of the parts without de-

parting from the spirit of the invention or sacrificing any of its attendant advantages, and the right is hereby reserved to make all such changes as fairly fall within the scope of the following 5 claims.

The invention is hereby claimed as follows:

1. A refrigerator comprising a cabinet and a plurality of refrigerated shelves mounted within the cabinet and made from a single strip of extruded material bent to provide a plurality of horizontal shelf portions and an integral riser portion connecting a pair of said shelf portions, said strip having spaced longitudinal ducts formed therein and extending in said horizontal 10 shelf and riser portions for the passage of refrigerant therethrough, and a foraminous grill forming a shelf extension supported in coplanar alignment with at least one of said horizontal shelf portions.
- 15 2. A refrigerator comprising a cabinet and a plurality of refrigerated shelves mounted within the cabinet and made from a single strip of extruded material having a plurality of spaced longitudinally extending ribs in a surface thereof, said ribs being formed with channels therein for the accommodation of a refrigerating medium, said strip being bent back and forth upon itself to provide horizontally extending and vertically spaced shelf and interconnected riser portions, some of said shelf portions having said 20 ribs at the upwardly facing surfaces thereof, a foraminous floor member supported on said ribs to form an article carrying shelf, and a foraminous member forming a shelf extension mounted 25 at an edge of at least one of said shelf portions and in coplanar alignment with the foraminous floor member thereon.
